FOLDING IRONING BOARD

Joseph E. Wood, Toronto, Ontario, Canada

Application January 9, 1952, Serial No. 265,637

1 Claim. (Cl. 38—117)

1 The invention relates to folding ironing boards as described in the present specification and shown in the accompanying drawings that form a part of the same.

The main object of the invention is to provide an ironing board having a work table of generous dimensions and a sturdy supporting structure therefor, both of which may be folded into a compact body wherein the supporting structure lies between folded sections of the table so that in its folded condition the device will present a smooth exterior, thus making the device particularly adaptable for storing in clothes closets and other likely congested places.

With the above and other objects in view the invention consists in the novel features of construction, arrangements and combinations of parts set out in the present specification and more particularly pointed out in the claim for novelty following.

In describing the invention reference will be made to the accompanying drawings, in which—

Figure 1 is a side elevation of my improved folding ironing board in its completely folded condition.

Figure 2 is a side elevation of the device as it appears in the process of being extended to its usable position.

Figure 3 is a perspective view of the under side of the device in its erected condition.

Like numerals of reference indicate corresponding parts in the various figures.

Referring now to the drawings. In view of the fact that the device as a whole is commonly known as an ironing board it has been thought desirable for purposes of clarity to refer herein-after to that part of the device on which the ironing is done as a table and in the drawings this table is designated generally by the reference character A.

The table A comprises two sections 1 and 2 respectively, preferably boards, which when placed in endwise relation to one another will conform substantially to the conventional ironing board, the section 1, hereinafter called the rear section, being of rectangular shape in plan and the forward section or leaf 2 being of the same width as the section 1 at the end thereof which abuts the said section 1 and being reduced towards its front end, as shown at 3, to conform to conventional practice.

The table sections 1 and 2 are hinged to one another so that the forward section, or leaf, can be swung backwardly to a position paralleling the under face of the section 1, but spaced therefrom,

whereby the device can be folded to occupy a relatively small space when not in use.

The hinge connection between the sections 1 and 2 comprises hinge plates 4 and 5 secured to the under sides of said sections respectively and extending over the respective under faces of the table sections for considerable distances from the meeting edges of said sections and terminating somewhat short of, and equi-distant from, the side edges of said sections in outwardly turned flanges 6 and 7 respectively. The flanges at the corresponding sides of the table are aligned endwise and extend parallel with the side edges of said table sections. The hinge plates 4 and 5 are provided at their meeting edges with endwise extensions 8 and 9 extending laterally therefrom and each being turned outwardly at right angles to the plates and then turned towards the other plate and then curved inwardly to provide endwise aligned sleeves for the reception of a hinge pin 10 on which the forward section can swing to and from its extended position.

The flanges, at the corners of their inner ends, are enlarged outwardly to provide shallow ears 11 for the purpose to be explained fully hereinafter, and the edges of the flanges 6 of the hinge plate 4 are provided with aligned recesses 12 for the purpose of receiving the said ears in the folded condition of the table sections.

The sleeves formed by the extensions 8 and 9 are so located that the hinge pin 10 will lie at substantially the outer edges of the flanges 6 and 7 so that in the folded condition of the table the outer edges of the flanges carried by the plate 5 will lie against the outer edges of the flanges carried by the plate 4 with the ears 11 lying within the recesses 12 respectively.

The table is adapted to be held supported in its erected condition for use by means of a foldable understructure which when extended is adapted for ground engagement at three points, two of which points are at opposite sides of the table beneath the rear end and the other of which points is in the transverse centre of the table beneath the forward end.

In the front supporting means for the main table section and the leaf section 2 a single leg is provided comprising an upper section 13 of substantially U-shape in cross section open towards the rear and a ground engaging section 14 pivoted at its top end within the upper section near the lower end of the latter on a pin 15, whereby said lower section may be extended into engagement with the ground, or folded upwardly to a position within the upper section. The up-

per leg section is fixed at its top end to the hinge pin 10 in the transverse centre of the table so that it can be readily swung rearwardly and upwardly into a position parallel with the table section 1.

16 is a bracing member which in the erected condition of the device extends upwardly at a forward angle from pivotal connection with the upper leg section at the point of connection between the upper and lower leg sections into endwise abutting engagement with a stop block 17 fixed to the under face of the table section 2. This bracing member serves to hold the leaf section 2 to its proper endwise relation with the section 1 and also to limit the forward swinging movement of the front leg so that said leg will assume a slightly forwardly inclined position.

The bracing member 16 is similar in cross sectional contour to the upper leg section 13 but is of sufficiently greater cross sectional dimensions to permit of its embracing said leg section in the folded condition of the device.

The bracing member 16 is cut away at its lower end to provide opposed apertured lugs 18 which embrace the upper leg section and are pivoted thereto by means of the pivot 15 which extends through the apertures in the lugs, so that the said member can be swung from a position embracing the upper leg section to a position with its free end engaging the stop member 17 carried by the table section 2.

19 and 20 are stays engaging the upper leg section 13 at opposite sides thereof near its lower end for the purpose of holding the front leg against lateral movement. These stays consist of rigid metal straps pivotally secured at their top ends by means of pins 21 to the ears 11 of the flanges 7 at opposite sides of the upper leg section and converging to embracing engagement with the opposing lugs 18 of the bracing member 16, to which latter they are pivoted by means of the pin 15. It will thus be seen that the stays 19 and 20 while acting to prevent lateral movement of the front leg under strain will move with said leg to and from its folded position.

In the rear supporting means for the table, 22 is a hollow bracket secured to the under side of the table section 1 at the rear end thereof and open lengthwise of the table, the said bracket being of the same width transversely of the table as the hinge plates 4 and 5 and being aligned therewith longitudinally of the table. This bracket has plane sides 23 extending at right angles to the table in longitudinal alignment with the corresponding side flanges 6 and 7 of the hinge plates and being of considerably greater depth than said flanges.

As stated previously herein two legs are employed to support the table at its rear end. These legs comprise upper sections 24 and 25, consisting of elongated rigid members of substantially U-shape in cross section positioned with their open sides forward, and being pivotally supported at their top ends on pins 26 which extend laterally from the sides 23 of the bracket 22, and ground engaging sections 27 and 28. The lower leg sections have their upper ends loosely fitting within the lower ends of the respective upper sections and pivotally secured therein by means of pins 29 and 30 respectively which extend across the openings in the upper sections at points somewhat above the lower ends of the upper leg sections and through the lower leg sections at points sufficiently close to the top ends thereof to allow the lower leg sec-

tions to swing freely from positions entirely within the upper sections, as in the folded condition of the device, to downwardly extended positions.

As hereinabove stated, the sides 23 of the bracket 22 are of considerably greater depth than the flanges 6 and 7 of the hinge plates. This allows the pivotal connections between the rear upper leg sections 26 and 27 and the supporting bracket 22 to be sufficiently farther removed from the lower face of the table than are the points of connection of the stays 19 and 20 with the ears 11 that the said rear legs in the folded condition of the device will lie outside the said stays and the front leg.

The rear legs are held against spreading by means of crossed stays 31 and 32, the stay 31 connecting the top end of the upper leg section 24 with the upper leg section 25 near the bottom end of the latter, and the stay 32 connecting the top end of the upper leg section 25 with the leg section 24 near the lower end of the latter.

Collapsible brackets comprising elongated, rigid strap-like sections 33 pivoted at their one ends to the flanges 6 at opposite sides of the table and sections 34 pivotally secured at their one ends to the respective outer ends of the said brackets 33 and at their other ends being fulcrumed on the pivot pins 29 and 30 respectively, provide means for limiting the rearward movement of the rear legs to the predetermined rearward inclination best calculated to hold the table steady in the erected condition of the device.

The sections 33 are provided outwardly of their pivotal connections with the sections 34 with laterally extending fingers 35 adapted in the extended condition of the brackets to embrace the corresponding edges of the associated sections 34 and enter into slots 36 in the edges of the latter and thus limit the collapsing movements of the brackets to a direction towards the table.

The lower leg sections 14, 27 and 28 may, if desired, be provided with tips 37 of rubber or other suitable material, which will tend to prevent the legs from slipping on the supporting surface.

38 is a tray constituting an iron stand slidable in the bracket 22 from a closed position in the folded condition of the device to an open position rearwardly of the table in the erected condition of the device. This tray has a corrugated metal bottom 39 to support the flatiron when not in use, and peripheral walls of considerable depth to prevent the flatiron from falling from the stand. The front wall has an outwardly turned part 40 providing a hand grip for use in moving the tray inwardly and outwardly, and the inner end wall has a downward extension 41 projecting below the bottom of the bracket 22 to prevent complete withdrawal of the tray from said bracket.

The transposition of the device from one to its alternate condition is extremely easy of accomplishment. Assuming that the stand is in its erected condition and is to be brought to its folded condition as shown in Figure 1, it is simply necessary to raise the forward end of the table slightly which will release the brace 16 from the stop 17 and allow it to be swung rearwardly on its pivot 15 to embrace the upper leg section 13, which latter, after the lower leg section 14 has been swung rearwardly and upwardly into position within said upper section can be swung rearwardly towards the under side of the table.

The lower sections of the rear legs are then swung upwardly into the upper sections 24 and 25 and, after the brackets composed of the members 33 and 34 have been collapsed, the rear legs are swung towards the table as far as they will go. The front table section 2 is then swung inwardly over the folded supporting structure so that the latter will lie between the table sections 1 and 2.

While I have illustrated and described herein the present preferred form of construction for carrying out my said invention, this is capable of variation and modification without departing from the spirit of the invention, I, therefore, do not wish to be limited to the precise details of construction set forth, but desire to avail myself of such variations and modifications as come within the scope of the appended claim.

What I claim is:

In a folding ironing board, a table comprising a main section and a leaf section, hinge plates secured to the inner faces of said sections, respectively, said hinge plates having opposed curved end extensions cooperating to provide sleeves longitudinally aligned transversely of the table, a hinge pin engaging within said sleeves, said sleeves and said hinge pin being spaced inwardly from said main table section whereby said leaf section may be swung to a position parallel with but spaced from said main section, a bracket carried on the under side of said main table section near the end thereof farthest removed from said leaf section, said bracket having parallel side walls extending lengthwise of the main table section near opposite side edges of the latter, rear legs comprising upper sections of substantially U-

shape in cross section and lower sections pivotally connected at their top ends to and within said upper sections, respectively, near the lower ends of said upper sections whereby the lower sections are movable to positions within said upper sections, said upper sections being pivotally supported from the sides of said bracket for swinging movement towards and away from the main table section, a front leg comprising upper and lower sections pivotally connected in end-wise overlapping relation whereby the lower section may be swung inwardly parallel with the upper section, the upper front leg section being fixed to said hinge pin medially of the ends of said hinge pin for movement therewith, a support for said leaf section pivotally connected at its one end to the upper front leg section and swinging to a position wherein its free end will assume a position beneath and provide a support for said leaf section, an abutment for the free end of said support fixed to the lower face of said leaf section, and collapsible bracing means for said rear and front legs.

JOSEPH E. WOOD.
